SHOCKPROOF CONNECTOR DEVICE

Joseph F. O'Brien, Jersey City, and Earl S. Boynton, East Orange, N. J., assignors to John B. Pierce Foundation, New York, N. Y., a corporation of New York

Application June 3, 1944, Serial No. 538,642

18 Claims. (Cl. 200—51.09)

1

The present invention relates to improvements in electrical plug connecting devices.

An object of the invention is to provide an improved connecting device such as a receptacle, or outlet or like connecting device for an electrical plug or like electrical connection member having flat face terminals the edges of which are rectilinear, wherein the metal elements accessible through the openings of such device, at the stage of non-association with the plug, are "dead," thus insuring safety against tampering or other unwise act, such as a child or other person inserting a hairpin or wire within such opening.

Another object of the invention is to provide an improved connector device applicable for electrically connecting the conductor or conductors leading to an electrical device, whereby the electrical circuit through the metallic elements of such connector device accessible from the exterior of such electrical device is automatically broken upon disconnecting a conventional electrical plug or equivalent with respect to such connector device.

Such arrangement obviates the need of a switch either in the immediate circuit of the electrical device or in association with the connector device, and also precludes arcing upon separation of the terminals of the electrical plug with respect to the metallic elements of the connector device accessible exteriorly thereof.

More specifically, pursuant to the invention, the receptacle, outlet or like connecting device associated with an electrical plug or like electrical connection member having flat face terminals the edges of which are rectilinear, is provided with a set of contact elements which are directly connected with the conductors leading from a source of electrical current, such contact elements being designated herein as "live" contact elements; associated with such "live" contact elements, respectively, are circuit-closing elements having flat faces which elements are suitably spaced relative to such "live" contact elements at the stage of non-insertion of the plug and are accordingly "dead." Such circuit-closing elements are provided with flat faces which are located in substantial alignment with the openings of the receptacle, outlet or like connecting device, whereby upon insertion of the flat faces of the terminals of the plug and engagement of the flat faces of such circuit-closing elements, such circuit-closing elements are displaced and are brought into electrical engagement with the "live" contact elements and thus effect electrical circuit closing.

Preferably, such circuit-closing elements are formed and arranged relative to the openings of the connecting device, whereby a snap action is afforded with respect to the mutually engaging portions of the circuit-closing elements and the

2

"live" contact elements upon withdrawal of the terminals of the plug or the like.

A further feature of preferred embodiments of the invention resides in the formation or arrangement of the contact-making elements whereby a firm mechanical grip upon the flat face terminals of the plug or the like is secured, thereby insuring maintenance of positioning of the plug at the stage of insertion, thereby safeguarding against loose electrical connection or accidental disconnection.

Among the structural and functional features of preferred embodiments of the invention are simplicity of assembly of the component parts, with attendant low cost of manufacture, certainty of operation under normal use, maximum surface contact engagement of the respective electrical conducting parts, and avoidance of joints in the path of the electric current under current-flow conditions.

In the accompanying drawings:

Fig. 1 is a central sectional elevation of a preferred type of embodiment of the invention in association with a conventional electrical plug having flat-faced terminals the edges of which are rectilinear, the body of such plug being shown in elevation. This view illustrates the flat-faced terminals of the plug in full inserted position and the contact-making elements in engagement with the "live" contact terminals. Fig. 1 illustrates the embodiment in the form of a wall receptacle.

Fig. 2 is a central sectional view similar to that of Fig. 1, showing the plug in partly inserted position relative to the contact-making elements, at which stage the contact-making elements are "dead."

Fig. 3 is a plan view of another embodiment of the invention, comprising a double receptacle. A conventional plug is shown in full inserted position and the circuit-closing elements in closed-circuit position with respect to one of the receptacles.

Fig. 4 is a central sectional view of Fig. 3.

Fig. 5 is a rear view of the embodiment shown in Figs. 3 and 4.

Fig. 6 is a longitudinal sectional view of the double receptacle taken on line 6—6 of Fig. 3, omitting the face plate and its securing means.

Fig. 7 is an exploded perspective view of a single contact-making element associated with a double contact terminal, such as may be employed in the embodiment illustrated in Figs. 3 through 6.

Referring to the embodiment shown in Figs. 1 and 2, the electrical plug 10 is shown of conventional construction having flat-faced terminals the edges of which are rectilinear; as is apparent, any suitable type of electrical plug having flat-faced terminals the edges of which are rectilinear, is applicable in conjunction with the variant

forms of connecting devices constructed pursuant to the invention, the essentials of such plug being that it is provided with the above stated terminals 11, 12 and that such terminals be insulated and protected by the body of the plug at the stage of flow of the electrical current through the terminals 11, 12.

The connecting device shown in Figs. 1 and 2 is of the wall-receptacle type, indicated generally 13, serving as an illustration of all types of electrical connecting devices applicable under the invention. Specifically, as is illustrated in Figs. 1 and 2, the receptacle box is indicated at 14, which may be located in a suitable opening 15 formed in a wall or partition, indicated at 16, and provided with a face-plate 17.

Such receptacle is shown comprising a hollow housing 18, preferably of electrical insulating material, its face member 19 having the conventional openings 20, 21, for the reception of the terminals 11, 12 of a suitable electrical plug. The face member 19 may include as an integral portion thereof a partition 22 serving to effectually subdivide the hollow interior of the housing 18. The face member 19 and its thus combined partition 22 may be molded integrally with the side walls of the housing, in which construction the bottom 18a is molded separately and these parts assembled by any suitable means, such as fastening screws 23. Or, as shown in Figs. 1 and 2, the bottom 18a may be molded integrally with the side of the housing and the face member 19 molded separately, and secured similarly in assembled position.

The contact-making elements are indicated at 25, 26 and are shown of a flattened general S-shape. Preferably, such contact-making elements are located to be self-supporting and be maintained in position within the respective sub-compartments of the housing 18. The contact terminals are indicated at 27, 28, and as shown in Figs. 1 and 2 are in the form of flat-faced strips of brass which are secured to the inner faces of opposing side walls of the housing 18, through which walls project their binding posts 29, 30, the latter being arranged for good electrical connection with suitable electrical feed conductors, indicated at 31, 32.

The contact-making elements 25, 26, and the contact terminals 27, 28, are of electrically conducting material, preferably of resilient metal. The contact-making elements 25, 26 are desirably of resilient metallic material.

As appears in Fig. 2, at the stage of non-insertion of the terminals of the plug, or partial insertion of the plug terminals 11, 12, the contact-making elements 25, 26 are suitably spaced with respect to the contact terminals 27, 28, to insure that the contact-making elements 25, 26 are "dead." To obtain such objective and to effect the stated self-support and maintenance in self-positioning, it is desirable to lodge the contact-making elements at their respective bend portions indicated 25a and 26a in grooves or the like, indicated at 18b, which may be formed integral with or secured to the bottom 18a of the housing 18. Such self-support and self-maintenance in position may be further effected by the provision of the flanges 19a formed integral or attached to the inner face of the face member 19. Such construction is advantageous in that the contact-making elements 25, 26 may be initially loosely placed respectively relative to the flanges 19a, 19a, and the grooves 25a and 26a, and upon tightening the screws 23, or equiva-

lent, the contact-making elements 25, 26 are properly located within the housing 18.

Assuming the terminals 11, 12 of the plug 10 are positioned partially within the outlet openings, as is indicated in Fig. 2, whereat their extremities touch the contact-making elements 25, 26, now upon applying pressure through the body of the plug to force its terminals 11, 12 into the bight between the arcuate bends of the flattened S-shaped elements, their free ends 25c, 26c are displaced toward and into electrical engagement with the juxtaposed portions 27a, 28a of the terminals 27, 28, thus effecting circuit-closing, namely, say, from the feed conductor 31 through the binding post 29, thence its contact terminal 27, thence the therewith associated contact-making element 25, to the plug terminal 11, and from the plug terminal 12 to its associated contact-making element 26, thence the associated contact terminal 28, its binding post 30 and finally to the feed conductor 32, as shown in Fig. 1.

Upon withdrawal of the plug 10 and its terminals 11, 12, to the position, say, indicated in Fig. 2, the displaceable portions of the contact-making elements 25, 26, by reason of their resiliency, spring back to their respective "dead" positions. To safeguard against pitting due to arcing of current, it is desirable to provide the respective contact-engaging portions of the contact-making elements and the contact terminals with silver or like facing, as by inlaying their respective portions with such protective metal, as is indicated at 25c, 26c, and 27a, 28a.

The terminals of conventional electrical plugs 35 are usually each equipped with a perforation within the body of the terminal adjacent its free end, such as are indicated at 11a, 12a, respectively, and advantage may be taken of such apertures to provide protuberances, see 25d, 26d, to be received within such apertures when the plug terminals are in fully inserted position, thus affording additional means for retaining the plug terminals against unintentional displacement. Such protuberances serve also, at the stage of initial withdrawal of the plug terminals, to "cock" the free end portions 25c, 26c, of the contact-making elements, and thus enhance the speed of circuit-breaking between the contact-making elements 25, 26, and their respective contact terminals 27, 28, approximately at the stage when the tips of the plug terminals are moved out of contact with the displaceable portions of the contact-making elements.

55 As shown in the drawings, it is advantageous to form the contact-making elements of flat stock and to arrange the contact-making elements within the housing to be engaged by the flat faces of the plug terminals, thus affording face-to-face engagement with attendant friction between the stated parts. Such face-to-face engagement is illustrated in Fig. 2 at the stage of initial engagement of the lower portion of each plug terminal with the displaceable portion of its associated contact-making element. Upon movement 60 to the final inserted position of each plug terminal, as illustrated in Fig. 1, the flat face of the end of such plug terminal is brought into face-to-face engagement with the displaceable part of its associated contact-making element, thus affording double face-to-face engagement during the stage of current flow.

65 Figs. 3 through 6 illustrate an embodiment of the invention as applied to a double outlet or 70 double convenience receptacle and the parts cor-

responding to those shown in Figs. 1 and 2 are designated by like reference characters.

Such double outlet or receptacle is conveniently secured within an outlet box 35 as by means of a conventional strap or equivalent having securing flanges, designated at 36, 36, for appropriate attachment as by screws 37.

It is observed that the housing of the double outlet or receptacle is illustrated as having its face member 19 molded integrally with its side walls and its bottom 18a molded separately, and the assembly secured by screws 23.

It is desirable to form the contact terminals of the double outlet or receptacle type of a single strip of metal, as illustrated in Fig. 7, with reference to the double contact terminal 28. As shown individually in Fig. 7, and in assembly in Fig. 6, each double terminal 28, and likewise the double terminal 27, may be bent outwardly, as indicated at 33, to protrude through suitable openings 34, 34, in the housing 18, thus affording secured lodgement of the contacts 27, 28, within the housing. Such lodgement may be enhanced by notching the contacts to form ears or extensions, as is indicated at 38, see also Fig. 6, and seating such ears or extensions within suitable slots, indicated at 39, which may be molded or formed within the housing 18.

Also, the contact-making elements 25, 26 may each be provided with the oppositely projecting ears, such ears 26e, 26e, for the contact-making element 26 being shown in Fig. 7; such ears are lodged within notches 40, molded or formed within the housing body 18. Fig. 6 shows the ears 25e of the element 25 and the ears 26e of the element 26, with reference to the double embodiment, and similar ears may be provided in the single receptacle embodiment illustrated in Figs. 1 and 2.

As shown in Figs. 1 through 7, each contact-making element comprises a part which is lodged within the housing to be stationary in relation thereto, as above set out, and another portion which is displaceable relative to its lodged portion, the displaceable portion being connected with such lodged portion by a reentrant or equivalent formation, the reentrant portion being positioned to be in substantial alinement with an opening in the receptacle housing whereby upon initial positioning of the free end of a plug terminal within a receptacle opening, such free end engages such displaceable portion in leverage relation and upon applying force through the body of the plug, the plug terminal displaces under leverage such displaceable portion to effect good electrical engagement of its free end with the contact of the receptacle. Accordingly, each plug terminal serves not alone the conventional function of conduction at the stage of current flow but also to positively effect and maintain closure of the electrical circuit.

It is apparent that the invention is applicable for receptacles, outlets and other connector devices adapted for association with plugs having three or more terminals, or having but a single terminal, as in a simple make-and-break connector attachment. The invention is also applicable for two-pole receptacles, outlets or other connector devices wherein a contact-making element is employed solely in association with the "live" contact of the connector device; also in polarized, i. e., three-pole or other types of receptacles, outlets and other connector devices solely in association with the "live" contact or contacts.

As is apparent, the contact-making element pursuant to the invention comprises a portion or part constructed or arranged to be stationary relative to the housing or equivalent of a receptacle, outlet, or other connector device, and a portion or part of electrically conductive material which is displaceable relative to the previously named portion or part, such displaceable portion or part being electrically insulated with respect to the electrical contact of such connector device at the stage of non-flow of the electrical current, but displaceable by the terminal of a plug or equivalent to effect electrical engagement with such electrical contact.

It is also apparent that it is advantageous to construct the contact-making element of electrically conducting material and to provide resiliency with respect to its displaceable portion or part.

It will be observed with respect to receptacles, outlets, and other connector devices having two or more electrical contacts and therewith associated contact-making elements, the latter having their displaceable portions or parts opposingly related with respect to one another, as herein set forth, that the forces of reaction brought about by the leverage action upon the displaceable portions or parts of the respective contact-making elements upon insertion of the terminals of a plug, are counter-balanced with respect to the plug terminals by the stationary portions or parts of the contact-making elements, thus facilitating the operation of inserting and seating the plug terminals in current-flow position.

From the above, it is apparent that embodiments of the invention possess simplicity of construction, favorable for low-cost production, minimum heating loss and consequent maximum current flow under circuit-closing condition, ruggedness of construction, insuring long life, and other advantages, as will be readily understood by these skilled in the art.

What we claim is:

1. For use with a conventional electrical plug or like connection member having flat-faced terminals, the edges of which are rectilinear, connecting means comprising a hollow casing provided with openings for the reception of the flat-faced rectilinearly-edged terminals of the plug, live electrical elements adapted to be connected to electrical conductors, and circuit-closing elements having flat faces arranged to be engaged with the flat faces of the terminals of the plug and upon movement of the plug terminals to be brought into electrical engagement with said live electrical elements.

2. For use with a conventional electrical plug or like connection member having flat-faced terminals, the edges of which are rectilinear, connecting means comprising a hollow casing provided with openings for the reception of the flat-faced rectilinearly-edged terminals of the plug, live electrical terminals adapted to be connected to electrical conductors, and circuit-closing elements having flat faces normally insulated from said live electrical terminals and arranged to be brought into electrical engagement respectively with said live electrical terminals by insertion of the terminals of the plug within said openings.

3. For use with a conventional electrical plug or like connection member having flat-faced terminals, the edges of which are rectilinear, connecting means comprising a hollow casing provided with openings for the reception of the flat-

faced rectilinearly-edged terminals of the plug, live electrical terminals adapted to be connected to electrical conductors, and re-entrantly formed resilient circuit closing elements disposed within the casing and normally insulated from said live electrical terminals and having flat faces at their re-entrant formations positioned to be engaged by the terminals of the plug and effect electrical engagement of said contact-making elements with said live electrical terminals.

4. A connector device comprising a hollow housing, said housing being provided with an opening for the reception of the terminal of a plug, an electrical contact insulatedly mounted within said housing, and circuit-closing means within said housing electrically insulated with respect to said electrical contact at the stage of non-flow of electrical current and arranged to effect circuit closing relative to said electrical contact upon insertion through said opening of the plug terminal, said circuit-closing means including an element bent upon itself and mounted within said hollow housing at its bend, said element having a flat face accessible through the opening of said housing for engagement therewith by the plug terminal.

5. A connector device comprising a hollow housing, said housing being provided with an opening for the reception of the terminal of a plug, an electrical contact insulatedly mounted within said housing, and resilient circuit-closing means within said housing electrically insulated with respect to said electrical contact at the stage of non-flow of electrical current and arranged to effect circuit closing relative to electrical contact upon insertion through said opening of the plug terminal, said resilient circuit-closing means including a part bent upon itself and mounted within said hollow housing at its bend, said element having a flat face accessible through the opening of said hollow housing for engagement therewith by the plug terminal.

6. A connector device comprising a hollow housing, said housing being provided with a plurality of openings for the reception of terminals of a plug or equivalent, electrical contacts insulatedly mounted within said housing, resilient circuit-closing means within said housing electrically insulated with respect to said electrical contacts respectively at the stage of non-flow of electrical current and arranged to effect circuit-closing relative to said electrical contacts respectively upon insertion through said openings of the terminals of said plug, said resilient circuit-closing means including a set of elements corresponding to the number of terminals of the plug, each being of wholly electrically conducting material, a part of which is bent upon itself and engaging an interior wall of said hollow housing at its bend, said elements having flat faces respectively accessible through the openings of said hollow housing for engagement therewith respectively by the plug terminals.

7. A connector device comprising a hollow housing, said housing being provided with a plurality of openings for the reception of terminals of a plug or equivalent, electrical contacts insulatedly mounted within said housing, resilient circuit-closing means within said housing electrically insulated with respect to said electrical contacts respectively at the stage of non-flow of electrical current and arranged to effect circuit-closing relative to said electrical contacts respectively upon insertion through said openings of the terminals of said plug, said resilient circuit-

closing means including elements of wholly electrically conducting material corresponding in number to the number of the terminals of the plug and disposed within said casing in opposing relationship with respect to said electrical contacts, said resilient circuit-closing means including a set of elements corresponding to the number of terminals of the plug, each being of wholly electrically conducting material, a part of which is bent upon itself and engaging an interior wall of said hollow housing at its bend, said elements having flat faces respectively accessible through the openings of said hollow housing for engagement therewith respectively by the plug terminals.

8. A connector device comprising a hollow housing, said housing being provided with a plurality of openings for the reception of terminals of a plug or equivalent, electrical contacts insulatedly mounted within said housing, and resiliency-provided circuit-closing means within said housing electrically insulated with respect to said electrical contacts respectively at the stage of non-flow of electrical current and arranged to effect circuit-closing relative to said electrical contacts respectively upon insertion through said openings of the terminals of such plug, said resiliency-provided circuit-closing means including elements of resilient electrically conducting material corresponding in number to that of the terminals of the plug, said elements having reversed bends respectively, and means for mounting said elements within said hollow housing to present face portions of said elements accessible through said openings of said hollow housing accessible to the plug terminals respectively for engagement therewith.

9. A connector device comprising a hollow housing, said housing being provided with a plurality of openings for the reception of terminals of a plug or equivalent, electrical contacts insulatedly mounted within said housing and resiliency-provided circuit-closing means within said housing electrically insulated with respect to said electrical contacts respectively at the stage of non-flow of electrical current and arranged to effect circuit-closing relative to said electrical contacts respectively upon insertion through said openings of the terminals of such plug, said resiliency-provided circuit-closing means being disposed within said housing in opposing relationship to said electrical contacts respectively, said resiliency-provided circuit-closing means including elements of resilient electrically conducting material corresponding in number to that of the terminals of the plug, said elements having reversed bends respectively, and means for freely mounting said elements within said hollow housing to present face portions of said elements accessible through said openings of said hollow housing accessible to the plug terminals respectively for engagement therewith.

10. For use with a conventional electrical plug or like connection member having flat-faced terminals, the edges of which are rectilinear, an outlet or receptacle comprising a hollow body, electrical contacts insulatedly mounted in said body and arranged to be connected with feed conductors; said housing being provided with openings for the reception of the terminals of a plug; and elements disposed within said housing normally out of electrical connection with said contacts, said elements having flat faces arranged to be respectively engaged by the terminals of such plug inserted through said openings and to be forced by

the plug terminals into electrical connection with said contacts.

11. For use with a conventional electrical plug or like connection member having flat-faced terminals, the edges of which are rectilinear, an outlet or receptacle comprising a hollow body, electrical contacts insulatedly mounted in said body and arranged to be connected with feed conductors; said housing being provided with openings for the reception of the terminals of a plug; and resiliency-provided elements disposed within said housing normally out of electrical connection with said contacts, said elements having flat faces arranged to be respectively engaged by the terminals of such plug inserted through said openings and to be forced by the plug terminals into electrical connection with said contacts.

12. For use with a conventional electrical plug or like connection member having flat-faced terminals, the edges of which are rectilinear, an outlet or receptacle comprising a hollow body, electrical contacts insulatedly mounted in said body and arranged to be connected with feed conductors; said housing being provided with openings for the reception of the terminals of a plug; and resiliency-provided elements disposed within said housing normally out of electrical connection with said contacts, said elements having flat faces arranged to be respectively engaged by the terminals of such plug inserted through said openings and to be forced by the plug terminals into electrical connection with said contacts, said resiliency-provided elements being disposed within said housing in opposing relation to said electrical contacts respectively.

13. A connector device comprising a hollow housing provided with mutually spaced openings, contacts for connection with the leads of a source of electrical energy mounted within said hollow body at locations inaccessible through said openings, and circuit-closing means disposed within said hollow housing and including elements of resilient electrically conducting material, each of said elements having reversely bent parts, means for mounting each said element to present the bight between its contiguous bent portions in alignment with one of said openings, said elements corresponding in number to that of said openings, whereby upon insertion of an electrical plug having terminals corresponding in number and mutual spacing to said openings, the plug terminals enter the respective bights of said elements to displace bent portions of said elements to respectively engage said source-connected contacts.

14. A connector device comprising a hollow housing provided with mutually spaced openings, contacts for connection with the leads of a source of electrical energy mounted within said hollow body at locations inaccessible through said openings, and circuit-closing means disposed within said hollow housing and including elements of resilient electrically conducting material, each of said elements having reversely bent parts, means for mounting each said element at its bend and to present the bight between its contiguous bent portions in alignment with one of said openings, said elements corresponding in number to that of said openings, whereby upon insertion of an electrical plug having terminals corresponding in number and mutual spacing to said openings, the plug terminals enter the respective bights of said elements to displace bent portions of said ele-

ments to respectively engage said source-connected contacts.

15. A connector device comprising a hollow housing provided with mutually spaced openings, 5 contacts for connection with the leads of a source of electrical energy mounted within said hollow body at locations inaccessible through said openings and circuit-closing means disposed within said hollow housing and including elements of resilient electrically conducting material, each of 10 said elements having reversely bent parts, means for mounting each said element freely at its bend and to present the bight between its contiguous bent portions in alignment with one of said openings, 15 said elements corresponding in number to that of said openings, whereby upon insertion of an electrical plug having terminals corresponding in number and mutual spacing to said openings, the plug terminals enter the respective bights of 20 said elements to displace bent portions of said elements to respectively engage said source-connected contacts.

16. A connector device for association with a conventional electrical plug or like connection member having flat-faced terminals, said connector device comprising a hollow housing provided with openings for the reception of the terminals of such connection member, mutually spaced electrical contacts insulatedly mounted within said housing and arranged for connection with an electrical supply, and circuit-closing elements insulatedly mounted within said housing and normally out of engagement with said mutually spaced electrical contacts respectively, said circuit-closing elements each including a resiliently mounted part, said resiliently mounted parts being provided with flat faces respectively disposed in substantial alignment with the paths of movement of the terminals of such connection member, and constructed upon face-to-face engagement with the flat faces of such terminals to be displaced respectively toward said contacts and in engagement therewith, thereby closing the electrical circuit through the connector device.

17. A connector device as defined by claim 16 in which said circuit-closing elements are each of flattened S-shape and its said resiliently mounted part is of arcuate formation having its free end projecting in the direction of its said associated contact.

18. A connector device as defined by claim 16 in which said circuit-closing elements are each of flattened S-shape and each provided with a protuberance forming with its said resiliently mounted part a bight, said bights of the respective circuit-closing elements being disposed in substantial alignment with the respective paths of movement of the terminals of such connection member.
